UNITED STATES PATENT OFFICE.

WILLIAM ALVIN SAUNDERS, OF BOSTON, MASSACHUSETTS, ASSIGNEE, BY MESNE ASSIGNMENTS, TO EMILY M. SAUNDERS, OF JAMAICA PLAIN, BOSTON, MASSACHUSETTS.

MANGLE.

1,135,725.

Specification of Letters Patent. Patented Apr. 13, 1915.

Application filed February 2, 1914. Serial No. 815,881.

To all whom it may concern:

Be it known that I, WILLIAM ALVIN SAUNDERS, a citizen of the United States, and resident of Boston, in the county of Suffolk and State of Massachusetts, have invented certain new and useful Improvements in Mangles, of which the following is a specification.

This invention relates to a mangle comprising a series of cloth covered ironing rolls, and a series of steam-heated ironing chambers having concave polished faces in close proximity to the peripheries of the rolls, the goods being ironed passing between the rolls and the ironing chambers.

The chief object of the invention is to enable the opposed surfaces of all the rolls and chambers to be simultaneously separated from operative relation to each other when the operation of the mangle ceases, so that the cloth coverings of the rolls will not be injured by the heat of the chambers when the machine is at rest.

The invention also has for its object to otherwise improve the construction of a mangle of this class in the particulars hereinafter described and claimed.

Of the accompanying drawings forming a part of this specification; Figure 1 represents an end elevation of a mangle embodying my invention; Fig. 2 represents a partial side elevation of the same; Fig. 3 represents a sectional detail view showing portions of one of the ironing rolls and the accompanying chamber; Fig. 4 represents a section on line 4—4 of Fig. 2, and an end elevation of the parts at the right of said line; Fig. 4^a represents a diagrammatic view showing the relative arrangement of the rolls and steam chambers; Fig. 5 represents a fragmentary plan view showing a part of one of the end members of the machine frame and one of the sliding bearings engaged therewith; Fig. 6 represents a section on line 6—6, Figs. 1 and 5; Fig. 7 is a side elevation of one of the ironing rolls; Fig. 8 is a fragmentary longitudinal section of the roll shown by Fig. 7; Fig. 9 is a section on line 9—9 of Fig. 8; Fig. 10 is an end elevation of the roll, one side being shown in section.

The frame of the machine includes two end members 12 having guides 13 and 14 for

upper and lower sliding bearings 15 and 16, each end member having two pairs of guides 13 and 14, and two sliding bearings 15 and 16. In the upper bearings 15 is journaled the shaft 17 of an upper ironing roll 18 and in the lower bearings 16 is journaled the shaft 19 of an intermediate ironing roll 20. The shaft 21 of a lower ironing roll 22 is journaled in fixed bearings 23 attached to said frame members. The ironing rolls have the usual cloth jackets 24, and each is constructed as described in detail hereinafter.

Opposite each ironing roll is a steam-heated ironing chamber having a polished concave ironing face substantially concentric with the corresponding roll, as shown diagrammatically by Fig. 4^a. The series of ironing chambers comprises a fixed upper chamber 25, a fixed intermediate chamber 26, and a vertically movable lower chamber 27, the fixed chambers 25 and 26 being suitably attached to the frame members 12, while the movable chamber is supported by levers hereinafter described. The sliding bearings of the upper and intermediate rolls are movable to move said rolls toward and from the fixed chambers 25 and 26, as indicated by the double arrows *x*, *y*, and the lower chamber 27 is movable toward and from the lower ironing roll, as indicated by the double arrow *z* (Fig. 4^a). Said movements are affected simultaneously by the adjusting mechanism hereinafter described, the rolls 18 and 20 being moved simultaneously in opposite directions and in substantially horizontal paths and the chamber 27 being moved at the same time in a substantially vertical path. The object of these movements is to enable the opposed faces of the rolls and chambers to be simultaneously separated when the machine is not in use, so that the cloth jackets of the rolls will not be injured by protracted close proximity to the heated chambers, and to be simultaneously restored to their pressing relations when the machine is to be operated.

As viewed in Fig. 4^a, the chamber 25 is located at the right of the roll 18 and the chamber 26 is located at the left of the chamber 20. The chamber 27 is located under the roll 22 and is adapted to raise the ironed goods to a folding table 30, the rolls

being rotated in the directions indicated by arrows and the arrangement being such that the goods entering between the upper roll and the upper chamber pass in a sinuous course from a guide 31 to the table 30 in contact with extended ironing surfaces. One side of the goods is ironed twice, first by the roll 18 and chamber 25, and then by the roll 22 and chamber 27, this being called the right side and having a higher polish than the opposite side, which is ironed but once, and by the roll 20 and chamber 26. The axes of the series of ironing rolls are not in the same vertical plane, but are in a plane which is inclined at about the angle indicated by Figs. 1 and 4. This arrangement reduces the height of the machine, and causes the goods to pass from one chamber and roll to the next in the sinuous path described without liability of being folded and wrinkled. The goods are guided to the folding table 30 by the rear edge of the chamber 27 as already described and are deposited right side downward on the table so that the attendant is enabled to fold the goods right side out, as is customary, by raising opposite ends of each piece from the table, and turning them inwardly upon intermediate portions of the piece.

30 The mechanism for simultaneously shifting the rolls 18 and 20 and the chamber 27 is preferably arranged as follows: 33 represents an operating shaft journaled in the bearing 34 attached to one of the frame members 12 (see Fig. 2) and provided at its outer end with a hand wheel 35 and at its inner end with a worm 36. 37 represents a shaft journaled in fixed bearings on the frame members 12 and provided with a worm gear 38 meshing with the worm 36 and with a small gear or pinion 39. 40 represents a larger gear journaled in a fixed bearing 42 (Fig. 2) and meshing with the smaller gear 39. To the shaft 41 of the gear 40 is attached a pinion or small gear 43. 44 represents a lever fulcrumed on a shaft 45 supported in fixed bearings 46 on the frame members 12. The longer arm of the lever 44 is provided with a segmental rack 47 meshing with the small gear 43. To the shorter arm of the lever 44 is pivoted at 48 a shoe 49 which supports the lower steam chamber 27. There are two levers 44, each having a shoe 49, said shoes being located at or near opposite ends of the chamber 27. The rotation of the operating shaft 33 by the hand wheel 35 causes the levers 44 to swing on their fulcrums and raise or lower the shoes 49 and the lower steam chamber 27 supported thereby, provision being thus made for vertically moving the chamber 27 away from the lower roll 22 when the machine is not in use.

The described movement of the levers 44 is utilized to move the bearings 15 and 16

simultaneously in opposite directions and in substantially horizontal paths to move the upper roll 18 toward and from the chamber 25 and the intermediate roll 20, toward and from the chamber 26, the levers 44 being connected with the sliding bearings 15 and 16 by the means next described.

50 represents a bell crank lever pivoted at 51 to the frame and having a slot 52 in one of its arms engaging a stud 53 on an 75 ear attached to the upper bearing 15. The other arm of the lever 50 is pivoted at 54 to one end of a connecting rod 55, the other end of which is connected by a stud 56 with an ear on the lever 44, said ear having a 80 slot 57 in which the stud 56 is movable. 58 represents another bell crank lever pivoted at 59 to the frame and having a slot 60 in one of its arms receiving a stud 61 attached to an arm on the sliding bearing 16. To 85 the other arm of the lever 58 is pivoted at 62 a link 63, the other end of which is pivoted at 54 to the lever 50 and to the connecting rod 55. It will now be seen that an upward movement of the lever 44 causes the 90 bell crank levers 50 and 58 to swing simultaneously in the directions required to move the upper roll 18 toward the left and the intermediate roll 20 toward the right from the positions indicated in Fig. 4, said rolls 95 being therefore simultaneously separated or moved away from the corresponding chambers 25 and 26. It will of course be understood that the boxes 15 and 16 at each end of the machine are adjusted in the manner 100 and by the means above described, there being two sets of bellcrank levers 50 and 58. It is obvious that a downward movement of the levers 44 will cause the rolls 18 and 20 to move toward the corresponding chambers 25 and 26.

The lower steam chamber 27 is loosely connected with the shoes 49, said chamber having a curved projecting bearing face 65 resting on a curved seat 66 formed on the 110 shoe 49 between two stop shoulders 67, which are arranged as indicated by Figs. 1, and 4 to permit limited movement of the face 65 between them. The seat 66 and face 65 are concentric with the concave 115 pressing face of the chamber 27. The levers 44 and shoes 49 constitute a simple and effective means for adjustably supporting the chamber 27. The object of the described loose engagement between the chamber 27 and the 120 shoes 49 is to maintain the concave pressing face of the chamber 27 substantially parallel or concentric with the periphery of the roll 22 when the chamber 27 is adjusted vertically. To the ends of the chamber 27 are 125 pivoted at 68 links 69, the outer ends of which are pivoted at 70 to the frame. These links prevent the chamber 27 from tipping on the shoes 49, so that when the machine is at rest and the chamber 27 is retracted not 130

part of the heated chamber can touch the cloth cover of the lower roll 22. Injury to said cover by heat is thus prevented.

The connecting rods 55 and the links 63 and 69 are preferably adjustable in length, as indicated by Fig. 4, each being practically a turn buckle and including a screw-threaded section and end sections engaged therewith in such manner that the rotation of the threaded sections will increase or decrease the length of the said connecting rods and links, provision being thus made for independently adjusting or varying the initial positions of the rolls 18 and 20 and 15 chamber 27.

I have found that there is sometimes a tendency of the goods to cling to the cloth cover of the upper roll 18, the goods containing more moisture at this part than in 20 subsequent parts of their path through the machine. To overcome this tendency I provide the chamber 25 with a rib or bead 72 projecting from the concave face of the chamber and having a rounded surface 25 adapted to compress the goods passing between it and the roll 18 and at the same time compress the cloth covering 24 of the roll. As the covering passes the bead 72 its effort 30 to expand loosens the goods from the cloth cover and counteracts the tendency of the goods to cling to the cover. Each of the steam chambers may be provided with a bead or projection for this purpose if desired.

35 The sliding bearings 15 and 16 rest on antifriction rolls 75 interposed between the bearings and their lower guides, as shown by Figs. 1, 5 and 6, said rolls having trunnions 76 engaged with flanges 77 on the 40 bearings as shown by Fig. 6. Said bearings 15 and rolls 75 guide the upper and intermediate ironing rolls in rectilinear paths so that when they are retracted from the chambers 25 and 26 no portions of their 45 cloth covering can remain in contact with the said chambers. The antifriction rolls obviate the necessity of lubricating the sliding bearings 15 and 16, so that there is no liability of soiling the goods by lubricating 50 material.

The ironing rolls are rotated by a driving shaft 78 through the train of gears 79, 80, 81, 82, 83, 84, 85 and 86 (Fig. 1). The gear 79 is attached to the driving shaft. The 55 gears 80 and 81 are attached to a shaft 87 journaled in bearings on the frame. The gears 82 and 83 are attached to a shaft 88 also journaled in bearings on the frame. The gears 84, 85 and 86 are attached respectively to the roll shafts 21, 19 and 17.

Each ironing roll is constructed as shown in detail by Figs. 7, 8, 9 and 10, which may be understood to represent the upper roll 18.

The body of the roll is composed of a hollow metal cylinder 90 and heads 91 inserted in

the ends of the cylinder and having flanges 92 bearing on said ends. The heads 91 have hubs 93 attached by set screws 94 and keys 95 (Fig. 10) to the shaft 17. Said shaft is provided within the cylinder 90 with hubs 96 attached to the shaft by set screws 97 and keys 98 (Fig. 9), the hubs 96 being uniformly spaced from each other and from the heads 91, as indicated by Fig. 7. Each hub 96 has a head or enlargement 99 provided in each of its four sides with dovetail guides 100, which are inclined relatively to the shaft 17 as shown by Fig. 8. With said guides are engaged dovetail slides 101 formed on supporting blocks 102 having segmental outer faces 103 fitting the internal surface of the cylinder 90. The supporting blocks have tapped orifices engaging the threaded inner ends of tension rods 104, the threaded outer ends of which pass freely through holes in the heads 91, and are provided with nuts 105 bearing on the outer sides of the heads 91. The operation of tightening said nuts causes the rods 104 to draw the supporting blocks 102 toward the heads 91, said blocks being at the same time forced radially outward by the inclined guides 100, and caused to bind firmly against the inner surface of the cylinder 90. The hubs 96 and supporting blocks 102 constitute 95 expandable heads adapted to be supported by the shaft while contracted, and expanded after the parts are assembled. The expanded heads firmly support the cylinder 90 at points between the outer heads 91, so that the cylinder is rigid from end to end and cannot be bent or sprung by the pressure of unusually thick parts of the goods against the periphery of the roll.

The hubs 93 are externally threaded and with their threaded portions are engaged sleeves 106 having clamping flanges 107, the beaded edges 108 of which confine the inwardly bent portions of the cloth covers 24 against the beveled edges 109 of the heads 91. The rotation of the sleeves 106 therefore causes the flanges 107 to either secure or release the ends of the cloth cover.

Hereinafter the levers 44 are termed chamber-adjusting levers, the levers 50 and 58, bearing-adjusting levers, and the links 63, connections between the chamber-adjusting levers, whereby they are caused to move in unison. The shoes 49 are referred to as supports for the lower chamber and the links 69 are referred to as movable means for preventing the lower chamber from tipping on the supports with which it is loosely connected. The chambers 25 and 26 are hereinafter described as facing in opposite directions to concisely point out the fact that the chamber 25 is at one side of the roll 18, while the chamber 26 is at the opposite side of the roll 20. The lower chamber 27, which faces upwardly 120

and is adapted to raise the goods to a point above the lowest part of the lower roll, enables the height of the series of rolls and of the machine as a whole to be reduced to the 5 minimum, the goods passing below the level of the table 30 on their way thereto. The relative arrangement of the rolls, in a series which is substantially vertical although somewhat inclined as shown from a vertical 10 plane, contributes to the reduction of the height of the upper roll and of the machine as a whole and at the same time reduces the length of the machine from front to rear as compared with a machine in which the 15 rolls are arranged more nearly in a horizontal plane.

The table 30 is located below the axis of the roll 22 so that goods delivered by the lower roll are free to swing outwardly from 20 the periphery of said roll by gravitation and drop upon the table, the roll having no tendency to carry the goods upwardly and between it and the roll 20.

Having described my invention, I claim:

25 1. A mangle comprising an upper roll, a lower roll and an intermediate roll arranged in a substantially vertical series, movable bearings for the upper and intermediate rolls, substantially horizontal guides for 30 said bearings, fixed bearings for the lower roll, upper, lower and intermediate ironing chambers coöperating respectively with said upper, lower and intermediate rolls, the upper and intermediate chambers being fixed 35 and facing in opposite directions, movable supports for the lower chamber, and mechanism for simultaneously moving the bearings of the upper and intermediate rolls and the supports of the lower chamber, said mechanism having provisions for moving the 40 upper and intermediate rolls simultaneously in opposite substantially horizontal directions on said guides, and for moving the lower chamber supports in substantially 45 vertical directions.

2. A mangle comprising an upper roll, a lower roll and an intermediate roll arranged in a substantially vertical series, movable bearings for the upper and intermediate 50 rolls, substantially horizontal guides for said bearings, fixed bearings for the lower roll, upper, lower and intermediate ironing chambers coöperating respectively with said upper, lower and intermediate rolls, the 55 upper and intermediate chambers being fixed and facing in opposite directions, chamber-adjusting levers fulcrumed to the supporting frame, lower chamber supports mounted on said levers and vertically movable 60 thereby, means for moving said levers to raise and lower the lower chamber, bearing-adjusting levers fulcrumed on the supporting frame and engaged with the said movable bearings to move the latter horizontally 65 on said guides, connections between 130

the said bearing-adjusting levers whereby they are caused to move in unison, and connections between the bearing-adjusting levers and the chamber-adjusting levers whereby movement is imparted from the latter to the bearing-adjusting levers.

3. A mangle comprising an upper roll, a lower roll and an intermediate roll arranged in a substantially vertical series, movable bearings for the upper and intermediate 70 rolls, substantially horizontal guides for said bearings, fixed bearings for the lower roll, upper, lower and intermediate ironing chambers coöperating respectively with said upper, lower and intermediate rolls, the 75 upper and intermediate chambers being fixed and facing in opposite directions, chamber-adjusting levers fulcrumed to the supporting frame, lower chamber supports mounted on said levers and vertically movable 80 thereby, means for moving said levers to raise and lower the lower chamber, bearing-adjusting levers fulcrumed on the supporting frame and engaged with the said movable bearings to move the latter horizontally 85 on said guides, connections between the said bearing-adjusting levers whereby movement is imparted from the latter to the bearing-adjusting levers, the said connections being variable in length to vary the 90 initial positions of the upper and intermediate rolls and the initial position of the lower 95 ironing chamber.

4. A mangle comprising an upper roll, a lower roll and an intermediate roll arranged in a substantially vertical series, movable bearings for the upper and intermediate 100 rolls, substantially horizontal guides for said bearings, fixed bearings for the lower roll, upper, lower and intermediate ironing chambers coöperating respectively with said upper, lower and intermediate rolls, the 105 upper and intermediate chambers being fixed and facing in opposite directions, chamber-adjusting levers fulcrumed to the supporting frame, lower chamber supports mounted on said levers and vertically movable 110 thereby, means for moving said levers to raise and lower the lower chamber, bearing-adjusting levers fulcrumed on the supporting frame and engaged with the said 115 movable bearings to move the latter horizontally on said guides, connections between the said bearing-adjusting levers whereby they are caused to move in unison, connections between the bearing-adjusting levers and the chamber-adjusting levers whereby 120 movement is imparted from the latter to the bearing-adjusting levers, the lower chamber being loosely mounted and laterally adjustable on its supports, and links pivoted to the lower chamber and to the supporting frame, 125 130

and adapted to prevent the chamber from tipping on said supports.

5. A mangle comprising a series of rolls comprising upper, intermediate and lower rolls arranged in a substantially vertical series, a series of ironing chambers coöperating with said rolls, the upper and intermediate chambers facing in opposite directions and the lower chamber facing upwardly and extending under the lower roll and being adapted to elevate goods passing between the lower roll and the lower chamber, and a folding table arranged to receive the goods from the lower roll and lower chamber, said table being located below the

axis of the lower roll, whereby goods delivered by the lower roll are caused to gravitate outwardly upon said table.

6. In a mangle, the combination of a cloth-covered roll, and an ironing chamber having a concave face provided near its delivering edge with a projecting rib adapted to compress the covering of the roll for the purpose specified.

In testimony whereof I have affixed my signature, in presence of two witnesses.

WILLIAM ALVIN SAUNDERS.
